BLINDSTITCH SEWING MACHINE.
APPLICATION FILED JUNE 17, 1905.

2 SHEETS—SHEET 2.

UNITED STATES PATENT OFFICE.

JOHN EDWARD FEFEL, OF MIDDLETOWN, CONNECTICUT, ASSIGNOR TO
UNITED STATES FELLING MACHINE CO., A CORPORATION OF NEW
YORK.

BLINDSTITCH SEWING-MACHINE.

No. 826,094.

Specification of Letters Patent.

Patented July 17, 1906.

Application filed June 17, 1905. Serial No. 265,637.

To all whom it may concern.

Be it known that I, JOHN EDWARD FEFEL, a citizen of the United States, residing at Middletown, in the county of Middlesex and State of Connecticut, have invented certain new and useful Improvements in Blind-stitch Sewing-Machines, of which the following is a specification.

This invention relates to that class of sewing-machines known in the art as "blind-stitch-machines."

My objects are, first, to produce a machine which shall be cheap of manufacture, simple of construction and operation, of great efficiency either at high or low speeds, and capable of forming a double-thread lock-stitch or a single-thread chain-stitch; second, to produce a machine which will admit of considerable range of relative adjustment of its parts to suit it to varying condition, and which will adjust itself automatically while in operation to varying thicknesses and other irregularities in the material to be stitched; third, to produce novel means for forming a ridge in the work to be stitched and means for adjusting the ridge-forming device whereby the depth of penetration of the needle may be nicely regulated; fourth, to produce a feed which will engage the work continuously, move it accurately and positively at the proper stage of operation, and grip the goods on the "wrong" side—*i. e.*, the side upon which the stitch will appear.

To this end the invention consists of the novel arrangement and combination of devices, which will now be described in detail, reference being had to the accompanying drawings, in which—

Figure 1 is a front elevation of a machine embodying my invention. Fig. 2 is a rear elevation of the same. Fig. 3 is an end elevation. Fig. 4 is a vertical section looking toward front of machine. Fig. 5 is a detail of a cam. Fig. 6 is a detail of an adjustable support. Fig. 7 is a sectional detail of a portion of the feeding device. Fig. 8 is a perspective of the bridge for forming a ridge in the work. Fig. 9 is a sectional detail. Figs. 10 and 11 are graphic representations of the manner of forming the stitch. Fig. 12 is a detail representing modifications, and Fig. 13 is a detail of a detached part.

Referring to the drawings by letters and nu-

merals, 1 is a base having a laterally-extending work-plate 2 and supporting the arm 3. A horizontal driving-shaft 4 is mounted in the arm and carries a pulley 5 and an eccentric 6, the latter being surrounded by a strap 7, to which is attached an upwardly-extending link 8, connected, by means of a ball-and-socket joint, with the lever 9. Lever 9 is pivoted in the arm 3 at 10 and is provided at its outer end with a downwardly-extending link 71, connecting said lever with a rocking needle-carrier 11. A curved needle 12 is secured to carrier 11 by means of a screw 13 and a threaded nut 14, the needle being placed between said carrier and said nut and the screw 13 set down hard to bind the parts together.

Hinged to the work-plate 2 and extending in a direction at right angles to the arc of movement of the curved needle is a device which operates in conjunction with the presser-foot, hereinafter described, to form a ridge in the material to be stitched in order that the material may be properly engaged by the needle. This device, which will be referred to herein as the "bridge" or "former," consists of a plate 14, hinged at 15 and having a flat upper surface 16 for a portion of its length and the double beveled surface 17 for the balance of its length, the beveled surface being located directly under the path of the needle. A pin projecting downwardly from the plate 14 is engaged by a flat spring 18, located on the under side of the work-plate 2, so that plate 14 is held pressed against the end of an adjusting-screw 19, provided with a jam-nut 20. By means of said screw and jam-nut the bridge or former may be raised or lowered and locked in the position required.

A thread-carrying looper 99, adapted to contact with the curved needle to form a double-thread lock-stitch, is carried on the end of a lever 21, pivoted to the standard 22, which is adjustably screwed to the work-plate, (see Fig. 6,) the other end of said lever being provided with a rounded head entering the cam-groove 23 in the face of the disk 24 on the driving-shaft 4. Lever 21 is tilted at an angle of about forty-five degrees relative to the plane of the work-plate, and the looper points downwardly at the same angle, the arrangement being such that rotation of the shaft 4 will cause the looper to rock in an arc

approximately intersecting the arc described by the curved needle, the looper passing above the needle at each stroke thereof forward as well as backward.

5 The presser-foot hereinbefore referred to consists of two separate members adapted to adjust themselves separately and independently to varying thicknesses or irregularities in the work and capable of being operated by 10 hand as a unit by means of a cam 25. In detail the presser-foot comprises two separate and distinct feet 26 and 27 and two separate vertical supporting-rods 28 and 29, each surrounded by a coil-spring 30, adapted to exert 15 a downward pressure upon its respective rod. The cam 25 rests upon the upper surface of arm 3 and is provided with two laterally-projecting pins, which engage vertical slots in the upper ends of the rods and serve to raise 20 and lower both members of the presser-foot simultaneously when the cam is operated. The feet 26 and 27 normally rest upon the upper beveled surface of the bridge or former 14, one on each side of the ridge-line, and are 25 shaped to conform to said surface.

Resting upon the flat surface 16 of the bridge or former is a feed-roller 32, having a toothed or roughened periphery and mounted on a shaft 33, carried in the lower forked 30 ends of two vertical rods 34 and 35. Preferably a slight degree of looseness or play for shaft 33 is provided for in this mounting in order that the roller may adapt itself to uneven thicknesses in the work. A spring 36, 35 anchored at 37 and passing under a tension-regulating device 38, has its free end bearing upon a pin 39, projecting from a block 40, said block being provided with forked ends embracing both rods 34 and 35. The block 40 rests upon pins 41, extending outwardly from 40 said rods, so that an even pressure is exerted by spring 36 upon both rods; but this arrangement does not interfere with the separate and independent movement of the rods 34 and 35 45 or the tilting of shaft 33 due to irregularities in the work. A cam 25^a, similar to cam 25, serves to raise and lower the rods 34 and 35 simultaneously in order to lift the feed-roller 32 from the bridge or former when it is desired to insert or remove the work.

Shaft 33 is provided at one end thereof with a socket adapted to receive the rounded end or head 45 of a rod 46, the other end of which is provided with a similar head 47. A 55 counter-shaft 49, located to the rear of shaft 4 and mounted in bearings 50 in the vertical part of arm 3, is provided with a socket 48, which receives the head 47. Pins 51 and 52, engaging in slots 53 54^a, respectively, complete 60 the connection, so that power transmitted to shaft 49 will be imparted to roller 32 whatever operative position said roller may occupy.

Shaft 4 is provided with a second eccentric 55 54, surrounded by strap 55, having an out-

wardly-extending slotted arm 56, and shaft 49 carries a loose collar 57, also provided with an outwardly-extending slotted arm 58 and a pawl 59, adapted to engage the teeth of ratchet-wheel 60, which is tightly mounted on 70 said shaft. A screw 61, passing through both slots and entering a thumb-nut 65, serves to lock the two arms 56 and 58 together, so that upon rotation of shaft 4 an intermittent step-by-step rotary motion will be imparted to 75 shaft 49. Obviously a longer or shorter step-by-step motion and a resulting longer or shorter stitch may be had as required by simply shifting the position of thumb-screw 61 in the slots.

62 represents a spring-detent engaging the teeth of ratchet 60 to prevent reverse movement of the shaft 49.

A needle traveling in the arc of a circle at high speed tends to straighten out by centrifugal action, and to prevent this I employ a needle-guide 66, adapted to lie under the needle and in contact therewith and to resist any tendency of the needle to leave its proper path of movement. This guide is formed 85 upon the end of a downwardly-depending rod 67, attached to a block 68, pivoted to the frame at 69. A curved arm 70, also attached to said block 68, projects into the path of movement of the lower end of the link 71, the 90 arrangement being such that the end of said link at the last portion of its downward stroke will contact with the curved arm 70 and move it downwardly for a short distance, thus causing the block 68 to rock on 95 its pivot and the guide 66 to be moved from beneath the needle and out of the way of the lower edge of the needle-carrier 11. A spring 73, attached at one end thereof to the frame of the machine and having its free end 100 engaging the extended upper end of rod 67, returns the arm and guide to normal position as soon as the link 10 begins its upward stroke. Arm 70 serves as a take-up for the 105 needle-thread 90.

The needle-thread is led from its spool 75 through the usual tension devices 76 (not a part of the present invention) to the eye 77. It is then looped around the arm 70, as shown in Figs. 1 and 2, and passed through eye 78, 115 from which it is led to eye 79 in a projecting finger forming a part of nut 114, hereinbefore referred to, thence to needle 12. The looper-thread 91 is led from spool 80 to eye 81, thence directly to the looper, the thread 120 passing through a hole 81^a in the rear of the looper, thence along a groove 82 in the upper surface of the same, Figs. 7 and 8, to the eye 83.

Fig. 9 illustrates the manner of forming 125 the ridge in the material to be sewed, 92 representing the folded material and the dotted line 93 the path of the needle, and Figs. 10 and 11 are graphic representations of the manner of forming the stitch. Beginning 130

with the position illustrated in Fig. 10, the needle moves to the right, pierces the material, and passes under the looper and through the loop *a*. The looper then backs out of the loop *b* and leaves the loop *a* around the needle, as shown in Fig. 11. At about the end of the forward stroke of the needle the take-up acts and sets the previously-formed stitch. The needle then retreats, the resistance of the work causing a loop to be thrown out, which will be caught by the looper on its forward stroke. The needle having backed clear out of the work and left its loop around the looper, the feed will operate and the work moved forward the length of one stitch, whereupon the above operation will be repeated.

It should be observed that the machine as above described is extremely simple in construction and convenient in arrangement. All the working parts are located above the work-plate and are of easy access for adjustment or repair. Furthermore, the flexibility of the various parts of the machine insures uniform excellence and accuracy of work.

It should also be noted that but one adjusting-screw is employed for the ridge-forming device and the feed-roller. The feed-roller being spring-pressed against the flat upper surface of the former will adjust itself to whatever position the latter may be raised.

In forming a single-thread chain-stitch it is only necessary to remove the looper shown in Fig. 1 and substitute one such as shown in Fig. 12. In this case a hook *x* is formed on the looper 99^a, which serves to carry forward the loop taken from the needle and hold it spread until the needle makes another trip and takes this spread loop from the looper, whereupon the looper makes another trip and takes another loop from the needle and carries it forward ready to be engaged by the needle. This is a well-known stitch, and it is not believed that a more detailed description is necessary.

I have disclosed herein but one embodiment of my invention; but I wish it to be understood that I do not confine myself to the specific construction shown and described.

Many changes might be made in various parts of the machine without departing from the spirit of my invention.

Having described my invention, I claim—

1. In a machine of the character described the combination of a base, a laterally-extending horizontal work-plate carried thereby, a curved needle supported above said work-plate and adapted to travel in the arc of a circle, a ridge-forming device adjustable toward and away from the needle, a flexibly-supported feeding-wheel or roller resting upon said ridge-forming device at the rear of the needle, a looper adapted to cooperate with said needle to form stitches and suitable mechanism for operating these several parts; the whole organization being mounted and

operating entirely above the work-plate and the looper being attached to a rocking member pivoted at an angle to said work-plate and adapted to carry the looper across the path of the needle, the looper passing above the needle both in its forward and backward strokes.

2. In a machine of the character described, the combination of a ridge-forming device comprising a bridge or former having a flat surface and two surfaces sloping downwardly from a common ridge, a presser-foot mechanism comprising two feet adapted to bear one against each of said sloping surfaces, the under sides of said feet corresponding to the configuration of said surfaces, a suitable feeding wheel or roller bearing against the flat surface of said bridge or former, means for rotating said wheel or roller, and suitable stitching-forming mechanism.

3. In a machine of the character described, the combination of a ridge-forming device comprising two surfaces sloping downwardly from a common ridge, a coacting presser-foot mechanism comprising two distinct and separately-movable members bearing one against each of said surfaces and corresponding in conformation thereto, vertical supporting-rods for said members, elongated slots in the said rods, springs for exerting downward pressure upon said rods independently, and a lifting-cam located between said rods and having lateral projections engaging the said elongated slots, substantially as and for the purpose set forth.

4. In a machine of the character described, the combination of a hinged ridge-forming device consisting of a bridge or former having a flat surface and two surfaces sloping downwardly from a common ridge, a spring normally pressing said bridge or former in one direction, an adjustable stop for the latter, a feed wheel or roller bearing against the flat surface of said bridge or former, flexible driving connections for said feed wheel or roller, and means for exerting yielding downward pressure upon the same, whereby an adjustment of the bridge or former will result in a corresponding adjustment of said feed wheel or roller.

5. In a machine of the character described, the combination of a ridge-forming device, a suitable coacting presser-foot mechanism, a curved needle located to the rear of said presser-foot mechanism, a feed-roller located to the rear of said needle and bearing upon said ridge-forming device, flexible driving connections for said feed-roller, and means whereby said ridge-forming device and said feed-roller may be adjusted simultaneously.

6. In a sewing-machine, the combination of a curved needle and suitable complementary stitch-forming mechanism, a pivoted carrier for said needle, a link connected with said carrier and with suitable mechan-

ism for imparting a rocking motion to the carrier, a pivoted needle-guide having a portion thereof normally projecting under the needle and another portion projecting into the path of said link, substantially as and for the purpose set forth.

7. In a sewing-machine having a curved needle and suitable complementary stitch-forming mechanism, a combined take-up and needle-guide comprising a pivoted body having a portion thereof lying in contact with the under side of said needle, and another portion thereof adapted to receive a loop in the needle-thread, and means substantially as described for rocking said body on its pivot at the close of the forward-stroke of the needle.

8. In a sewing-machine the combination

of a work-plate, a needle and needle-carrier arranged to move to and fro across said work-plate, a ridge-forming device pivotally mounted on said work-plate and spring-pressed away from the path of the needle, positive means for limiting such movement and means whereby the same is adjusted to vary the position of the ridge-forming device with respect to the path of the needle.

In testimony whereof I have signed my name to this specification, in the presence of two subscribing witnesses, this 10th day of June, 1905.

JOHN EDWARD FEFEL.
